UNITED STATES PATENT OFFICE.

JAMES CHURCHILL, OF REWARD, CALIFORNIA.

PITMAN-BOXING.

1,148,358.

Specification of Letters Patent. Patented July 27, 1915.

Application filed January 30, 1913, Serial No. 745,156. Renewed April 26, 1915. Serial No. 24,158.

To all whom it may concern:

Be it known that I, JAMES CHURCHILL, a citizen of the United States, and a resident of Reward, in the county of Kern and State of California, have invented a new and Improved Pitman-Boxing, of which the following is a full, clear, and exact description.

This invention is an improvement in boxings as used on pitmen for well boring, and the object of the invention is to provide an inexpensive, simple and reliable bearing which will automatically take up the wear between the wrist pin and the bearing blocks, and will make a quickly demountable accurate bearing.

The above outlined objects are obtained by providing in the pitman's body an angular aperture in which relatively movable bearing blocks are provided and a lever of the first-class associated with one of these blocks for operating same and the resilient member for normally forcing the bearing blocks together within the angular aperture.

Figure 1 is a side elevation of an embodiment of my invention with part of the face plate broken away; Fig. 2 is a section on line 2—2 Fig. 1; and Fig. 3 is a top plan view of the reciprocating bearing block.

Referring to the drawings, 10 represents the lower portion of the pitman, in which is provided centrally a rectangular aperture 11. Positioned in the aperture 11 against the shorter sides are blocks 12 and 13, of any suitable material, but preferably of cast iron. Threaded in one of these blocks is a plurality of pins 14 engaging the other block 13 loosely, so that by unscrewing the pins 14 from the block 12 the two blocks 40 are forced against the shorter sides of the aperture 11, and the pins are preferably close to the longer sides of the aperture 11 leaving sufficient space about the wrist pin. The blocks 12 and 13 have an edge portion 45 cut away so as to be flush with the surface of the body of the pitman, and engaging this cut-away edge and the face of the pitman is a plate 15 bolted or secured to the pitman in any desired way, and thereby preventing the displacement of the blocks 12 and 13. Intermediate the two blocks 12 and 13 another block 16 is provided which engages the pins 14 by means of notches 17 and with the lower block constitutes the 55 bearing for the wrist pin. The blocks 16 and 13 are preferably babbitted. The block

16 at its upper end opposite the bearing portion is provided with ears 18 through which projects a pin 19.

Engaging under the pin 19 between the 60 ears 18 is the curved portion 20 of a first class lever 21, the fulcrum 22 of which is positioned in the upper block 12. The free end of the lever 21 is provided with a handle 23, and the same side of the lever 65 is provided with a coil spring 24 connecting the lever with a pin 25 positioned in the body of the pitman, the tendency of the spring being to force the free end of the lever up and consequently forcing the 70 curved end 20 of the lever 21 downward, the lower curved portion of the curved end of the lever 21 bearing constantly against a flat portion 26 provided between the ears of the bearing block 16. To prevent accidental upward motion of the bearing block 75 16 the body of the pitman is provided with ratchets 27 engaging a finger portion 28 positioned on the free end of the lever 21 near the handle 23 and normally engaging 80 the ratchets.

It can be seen from the drawings that while the ratchets will not prevent the motion of the free end of the lever upward it will prevent its motion downward. A member 85 29 is provided in the handle 23 of the lever 21 by means of which the finger portion 28 can be made to disengage from the ratchets 27. A spring 30 is positioned in a closed portion on the lever 21 and forces 90 normally the pin 28 into the ratchets 27. To allow the block 16 to move up a portion of the block 12 is cut away, as shown in Fig. 1, permitting the displacement of the bearing block 16 into the position shown 95 in dotted lines in Fig. 1 and maintaining it there when necessary. A catch or pawl 31 is pivotally mounted on the body of the pitman by means of a pivot 32, and a spring 33 is constantly bearing against the pawl 31 100 maintaining it in a position to catch the lever 21 when the same is thrown in the position shown in dotted lines in Fig. 1, and preventing its going up under the action of the coil spring 24 unless the catch or 105 pawl 31 is disengaged from the lever.

As all the wear in the bearing provided in a pitman as used for well boring is in the lower portion or block 13, the upper block must be forced against the wrist pin 110 with sufficient force only to take up the wear produced in the lower block, and in

consequence of this the coil spring 24 is made sufficiently strong to produce this action. Any upward strain on the upper block 16 is contracted through the lever 21, finger 28 and ratchets 27. When it is desired to separate the pitman from the wrist pin or to repair the bearings, the lever 21 by means of the member 29 is first disengaged from the ratchets 27 and forced 10 down until the catch 31 engages the lever 21 whereby the bearing block 16 is carried up to uppermost position and maintained there. This permits the removal of the wrist pin or removal of the bearing 15 blocks 13 and 16 when necessary by first removing on one side the face plate 15 and then removing the blocks 13 and 16. The blocks 13 and 16 are removed by simply forcing the pin 14 up into the block 12. 20 This will allow the removal of the lower block and by removing the pin 19 from the ears 18 of the block 16, the same may be removed. When replacing the bearing blocks the action is reversed.

25 Having thus described my invention, I claim as new and desire to secure by Letters Patent:

1. In a pitman boxing, a body having a rectangular aperture, a block against each 30 of said shorter sides in said aperture, adjustable means engaging said blocks and maintaining the same against the shorter side, a block intermediate said blocks slidably mounted on said adjustable means and 35 forming with one of said blocks the bearing portion, face plates engaging said body and said blocks and preventing their side displacement, a lever of the first class engaging said first intermediate block and 40 having its fulcrum on the block not constituting the bearing portion with the intermediate block, resilient means connecting said body and the free end of said lever whereby said intermediate block is 45 forced against said block forming with it the bearing portion, and means on said body whereby said intermediate block can be placed in a predetermined position.
2. In a pitman boxing a body having an 50 angular aperture, blocks in said aperture,

means engaging said blocks and normally keeping said blocks against the opposite sides of said aperture, a block intermediate said blocks engaging the above-mentioned means, and a lever of the first class associated with said intermediate block for translating the same on said means, said intermediate block and one of said blocks forming the bearing portion, resilient means associated with said lever for normally forcing said intermediate block toward the block forming the bearing portion with it, and means on said body and said lever whereby said intermediate block can only move toward said block forming the bearing with it under the force of said resilient means.

3. In a pitman boxing, a body having a bearing therein formed of a fixed and a movable block, a lever of the first class associated with said movable block, a ratchet on said body, a member on said lever engaging said ratchet, a resilient member connected with said lever and said body and normally forcing said movable block 70 against the fixed block, and means on said body adapted to engage said lever when said lever is forced into a predetermined position.

4. In a pitman boxing, a body having a 80 bearing therein formed of a fixed and a movable block, said movable block having engaging means, a lever of the first class having the curved portion engaging slidably said means on said movable block, and 85 a coil spring associated with the opposite end of said lever and said body thereby normally forcing said movable block against said fixed block, said curved portion of said lever normally bearing against 90 said movable block under the action of said coil spring.

In testimony whereof I have signed my name to this specification in the presence of two subscribing witnesses.

JAMES CHURCHILL.
